O. C. WYSONG.

ABRASIVE APPARATUS.

APPLICATION FILED OCT. 23, 1907.

918,247.

Patented Apr. 13, 1909.

UNITED STATES PATENT OFFICE.

OLMEDO CORTEZ WYSONG, OF GREENSBORO, NORTH CAROLINA.

ABRASIVE APPARATUS.

No. 918,247.

Specification of Letters Patent.

Patented April 13, 1909.

Application filed October 23, 1907. Serial No. 398,753.

To all whom it may concern:

Be it known that I, OLMEDO CORTEZ WYSONG, a citizen of the United States, residing at Greensboro, in the county of Guilford and 5 State of North Carolina, have invented certain new and useful Improvements in Abrasive Apparatus, of which the following is a specification.

My invention relates to improvements in 10 abrasive apparatus. One of its objects is to provide a quickly operated mechanism for detaching and substituting abrasive belts of different lengths.

Another object is to provide improved 15 mechanism to automatically take up the slack of the sand-paper belt, and accurately regulate the tension thereof.

Another object is to provide means for 20 quickly changing and adjusting the tension through a considerable range.

Another object is to provide means for quickly converting the automatic adjustment to a positive and stationary adjustment, and to lock the adjustable element at 25 any desired position.

It further consists in certain details of 30 form, combination and arrangement, all of which will be more fully set forth in the description of the accompanying drawings, in

Figure 1 is a side elevation of one form of 35 my improved mechanism. Fig. 2 is a top plan view of a portion thereof. Fig. 3 is an enlarged end view of the portion illustrated in Fig. 2. Fig. 4 is a side elevation of a modified form of mechanism embodying my improvements. Fig. 5 is a detail sectional view on line *v v* of Fig. 4. Fig. 6 is a view similar to Fig. 5 showing a modification.

In the accompanying drawings, Figs. 1, 2, and 3, *A* represents a standard firmly secured to the floor or other foundation and carrying a power driven shaft *a*, which carries and drives a belt pulley *A'*. A slotted bracket *a'* is also preferably carried by standard *A*.

B represents a standard secured to the floor or foundation in line with standard *A* and at the desired distance therefrom required by the different classes of work to be treated. A traveling head *C* is mounted on standard *B* and travels horizontally relative to the standard, being guided preferably by a gib or way *b* on the standard.

D represents a plate pivotally attached at *d* to the head *C* and provided with journal boxes *d'* *d''* in which are journaled the ends

of a shaft *E* carrying a pulley *F*. The plate *D* is adjustable to secure the desired alinement or angular adjustment of shaft *E* by means of a lug *d''* on shaft *D* which is engaged at opposite sides by screw rods *c'* adjustable in ears *c''* of head *C*.

C' represents a stud bolt carried by head *C* and passing through a slotted opening *d''* in plate *D*, and by means of which plate *D* may 65 be firmly locked to its adjusted position. The adjustment of plate *D* causes the belt to travel over the center or at either side of the center of the pulleys as desired.

G represents an abrasive belt traveling 70 over pulleys *A'* *F* and adapted to treat a variety of work, whereby the belt is required to be frequently changed, and at times to run slack over the pulleys, at other times to run under uniform tension, and at 75 other times as indicated in Fig. 1 the work *g* is pressed down upon the belt forming a pocket in the belt at *g'* between the pulley *F* and the stationary form *g''*. In order to conveniently and quickly effect these various adjustments in the tension of the belt, and make changes thereof I preferably provide a rack *h* upon the head *C* which meshes with a gear *H* upon shaft *h'* journaled in standard *B*. A grooved pulley *h''* on shaft 85 *h'* has attached thereto a cord *h''* which hangs down from the pulleys and is adapted to receive a varying number of weights *h''* to regulate the tension on the belt *A*. When the tension is secured by means of the 90 weights acting on shaft *h'* and through gear *H* and rack *h*, the belt is held at a uniform tension at all times, and the head *C* travels toward the standard *A* when the work *g* is forced down upon the belt to form pocket *g'*, 95

and travels in the opposite direction when the work is removed without varying the tension. Where however the form *g''* is to be advanced beyond the face of pulleys *A'* *F* and the belt drawn across the form, a permanently slackened belt is preferable, and pulley *F* is forced toward standard *A* by turning wheel *h''* and head *C* is locked to standard *B* by means of set screw *I*. A pawl *h''* and ratchet wheel *h''* may be employed to temporarily hold the head *C* to its adjusted position toward standard *A* until after set screw *I* has been locked, when the pawl may be thrown out of engagement with the ratchet wheel.

In the modification shown in Figs. 4 and 5 both pulleys *A'* and *F* are carried upon a

frame J, which is pivoted to standard J' and adapted to be adjusted to varying angles. A yoke frame K is provided with journal boxes to receive the shaft of pulley F, said yoke frame having also a cylindrical shank K'. The shank K' is mounted to slide endwise in a socket J² of frame J and is preferably splined in said socket by means of a key K². Teeth k are cut upon the shank K', which teeth mesh with the teeth of gear k' journaled upon shaft k². A grooved wheel L has attached thereto a cord which is tensioned by a spring L' adjustable as to tension by a screw shank l. At the opposite side of the frame I preferably provide a ratchet wheel M and pawl m which may be temporarily engaged therewith when desired to lock the shank to position. A hand lever N assists in adjusting the shank K' to any desired position, and a set screw n enables the shank to be firmly locked to any desired position when required. In the modification Fig. 6 a weight P is employed in place of spring L' the cord p being guided by rollers along the side of frame J to a position near the standard J' where the weight would not interfere with the adjustment of frame J. Forms may be carried by bracket J³ and a table by bracket J⁴.

In practice a frequent change of belts is required to secure a belt with fine, coarse or medium abrasive material, or to secure a belt of the desired width. As these belts vary considerably in length, it is important to have quick means of adjustment to release the old belt and adjust the new one. This quick adjustment is attained by releasing the set screw I or n, the ratchet and pawl engaged, and the hand lever N or wheel h² used to counteract the weight or spring and pulley F fed toward pulley A' to slacken the tension on the old belt which is thrown off the pulley F. The new belt is then placed upon pulley A' and if necessary pulley F further adjusted toward pulley A' until the new belt will slip easily over pulley F, after which the pawl if used may be disengaged and set screw I or n tightened to lock the parts to the adjusted position, or the strain of the weight relieved upon to tension the belt, as required.

The mechanism herein shown and described is capable of considerable modification without departing from the principle of my invention.

Having described my invention, what I claim is;

1. In a mechanism of the character indicated, a pair of pulleys, an abrasive belt sup-

ported upon and driven by said pulleys, a traveling head carrying one of said pulleys, a rack on said traveling head, a gear in mesh with said rack, mechanism adapted to exert a substantially uniform force on said gear and rack to provide a quick adjustment of said pulley and an automatically yielding tension for said abrasive belt and means independent of said yielding tension to positively lock said traveling head to any desired position.

2. In a mechanism of the character indicated, a pulley journaled in a fixed position, a pulley journaled to a traveling head adapted to travel to and from said fixed pulley, an abrasive belt supported upon said pulleys and driven by said fixed pulley, a rack carried by said traveling head, a shaft journaled in a fixed position, a pinion carried by said shaft and in mesh with said rack, a pulley carried by said shaft, and mechanism exerting an automatically yielding tension on said last named pulley in a direction to strain said belt, a ratchet wheel carried by said shaft, and a pawl adapted to engage said ratchet wheel and to lock said shaft in opposition to said yielding tension.

3. In a mechanism of the character indicated, a pair of pulleys, an abrasive belt supported upon and driven by said pulleys, a traveling head carrying one of said pulleys, mechanism exerting a yielding tension on said traveling head, a pawl adapted to be temporarily employed to dog said traveling head in opposition to said yielding tension, and means for positively clamping said traveling head to its adjusted position.

4. In a mechanism of the character indicated, a pair of pulleys, an abrasive belt supported upon and driven by said pulleys, a traveling head carrying one of said pulleys, a rack on said traveling head, a shaft journaled in a fixed position and provided with a gear in mesh with said rack, a ratchet wheel on said shaft, a pawl adapted to be intermittently engaged with said ratchet wheel, and mechanism exerting a yielding force upon said shaft to turn said shaft and move said traveling head in opposition to said ratchet wheel and pawl.

In testimony whereof I have affixed my signature in presence of two witnesses.

OLMEDO CORTEZ WYSONG.
